UNITED STATES PATENT OFFICE

1,972,099

APPARATUS FOR CONDITIONING FLUIDS

Beverly P. Lientz, Kansas City, Mo.

Application May 9, 1928, Serial No. 276,282

1 Claim. (Cl. 196—116)

My invention relates to an apparatus for conditioning fluids and more particularly to the cracking of hydrocarbon oils in stills.

With present types of oil still furnaces it is a practice to pass a continuous stream of oil through a heat zone maintained at a temperature high enough to bring about the desired degree of conversion of the oil and to retain the oil in the heat zone for such appreciable interval of time as to effect its conversion. Under such practice the oil becomes overheated as a result of progressive increase of its temperature during its flow through the heat zone and is wasted by consumption.

15 It is the principal object of my invention to so control temperatures in the heat zone as to avoid losses due to overheating of the oil, by quickly heating the oil to the proper temperature during the first part of its travel through the heat zone, 20 and then maintaining the temperature of the oil stream substantially constant during the remainder of its travel through the still.

In practicing my invention I have provided improved details of furnace structure, the preferred 25 forms of which are illustrated in the accompanying drawings, wherein:

Fig. 1 is a longitudinal, vertical, sectional view through a furnace embodying my invention, on the line 1—1, Fig. 2.

30 Fig. 2 is a cross sectional vertical view through the furnace on the line 2—2, Fig. 1.

Fig. 3 is a plan view of the furnace, the roof of one of the burner compartments being broken away to illustrate the fresh air duct through 35 which air is supplied for supporting combustion.

Fig. 4 is a horizontal sectional view through the furnace on the line 4—4, Fig. 1.

Referring more in detail to the drawings:

1—2 designate side walls and 3—4 end walls 40 of a furnace of Dutch oven type enclosing a central heating chamber 5 covered by a roof 6 and combustion chambers 7 and 8 at the ends of the heating chamber, the latter formed by extending the lower portions of the side walls and, 45 offsetting the lower portions of the end walls with roof seals 9 and 10.

The walls of the furnace are supported upon suitable foundations and footings, indicated at 11 and a floor 12 of suitable construction extends 50 continuously beneath the heating and combustion chambers.

Extending crosswise of the furnace about midway thereof is a partition 13 cooperating with the end walls 3 and 4 in supporting a bank of heating coils 14 which extend longitudinally of

the furnace. The coils may be of any preferred type but are here shown as straight sections, the ends of which extend into recesses 15 formed in the end walls and there connected by return bend fittings 16 to form a continuous coil, the fittings being accessible through suitable doors 17 covering the recesses.

Similarly supported by the end walls above the bank of coils 14 and spaced therefrom, as at 18, is a second bank of coils 19, similar to the first bank, but preferably of greater number, with the lower coil of the upper bank connected with the lower coil of the lower bank, so that oil subjected to an intense heat applied to the lower coils may be quickly brought to the required temperature and then passes to the upper bank where it is maintained at a constant temperature, as presently described, the coils being of such combined length as to insure proper conditioning of the oil during its travel through the furnace.

Located at the outer ends of the combustion chambers 7 and 8 are arches 20, which extend across the chambers and are supported from the floor 12 by checkered walls 21 to provide air chambers 22 between the checkered walls 21 and the end walls of the furnace, the arches extending inwardly over the walls 21 to provide mixing chambers 23 which open into the combustion chambers.

Extending transversely below the air chambers 22 and opening thereinto through ports 24 are air supply conduits 25 connected through underground passageways 26 and ducts 27 with a pre-heater 28 (Fig. 3), through which air is drawn by motor operated fans 29 and delivered to the air chambers for supplying oxygen to burners 30. The burners may be of any preferred construction including nozzles 31 which project through the checker work of the walls 21 so that fuel from the nozzles and air issuing through the checker work from the air chamber are mixed and consumed in the combustion chambers.

Products of combustion pass upwardly from the chambers 7 and 8 through the heating chamber 5 over the heating coils 14 and 19 and are discharged through a plurality of vertical flues 32 in the roof 6 of the heating chamber into a longitudinal manifold 33 supported on the furnace roof. Some of the spent gases are discharged from the manifold into a pipe 34 leading from about the middle of the manifold and extending laterally and downwardly therefrom to discharge into a horizontal tunnel 35 through which they are conducted to a stack 36. The preheater 28 is projected into the tunnel so that

fresh air passed therethrough on its way to the mixing chamber is conditioned for supported combustion.

A major portion of the products of combustion 5 entering the manifold is, however, conducted back to the chamber 5 for recirculation to save its content of heat units and for the further purpose presently described.

Opening laterally from opposite sides and adjacent 10 the ends of the manifold 33 are return conduits 37 which extend downwardly near each corner of the furnace to connection with fan housings 38, mounted on concrete bases 39 and having discharge pipes 42 leading to tunnels 43 15 which extend beneath the furnace floor adjacent the discharge ends of the combustion chambers 7 and 8.

Each of the tunnels has ports 44 opening into a channel 45 formed in the furnace floor slightly 20 within the mouth of its relative combustion chamber so that the returned gases passing therethrough are discharged into the combustion chamber to co-mingle with fresh products of combustion and recirculate through the heating chamber.

Fans (not shown) contained within the housing are operated through shafts 46 from electric motors 47 to draw the gases from the manifold and discharge them into the heating chamber, 30 flow of the gases being regulated by dampers 48 located in the pipes 42 adjacent the inlet of the tunnels, as best shown in Fig. 2.

With the structure thus far described, products of combustion passed through both banks of coils would progressively heat the coils and should 35 the temperature of the gases be sufficient to crack the oil in the lower bank, then there would be overheating in the upper bank with resultant loss in product.

To insure heating of the oil to cracking temperature within the lower bank of coils and prevent overheating in the upper bank I inject currents 40 of cooler gases into the space between the banks across the line of flow of heating gases, thereby providing an insulating blanket of cooler gases 45 which retards travel of the heating gases to retain them in longer and more intimate contact with the lower bank and tempers them to prevent their overheating the oil in the upper bank 50 of coils.

Such currents of cooler gases preferably consist of products of combustion supplied through conduits 49 leading from the conduits 42 to horizontal manifolds 50 extending along the side walls exteriorly to the furnace and having short lateral discharge pipes 51 extending into openings 52 in the side walls of the furnace, which communicate with the space between the banks of coils, so that gases are delivered from the manifolds into the space 18 and across the line of flow of the heating gases for the purposes before mentioned.

Volume of flow of the cooling gases may be regulated to control temperature of the heating gases by a damper 53 in the conduit and a damper 54 in the pipe 42 adjacent the fan discharge, the damper 53 serving to control the minor flow of cooling gases to the manifold and the damper 54 to control the major flow to both the manifold and heating chamber.

With the furnace described I am able to quickly heat the oil to cracking temperature and maintain the heat for a sufficient time interval for properly conditioning the oil without overheating, and to adjust the temperatures to the requirements for treating different oils.

I have found a furnace constructed as illustrated and described well adapted for practice of the invention but do not wish to be limited to it in detail, and while I have referred to the cooling gases as products of combustion, other gases or atmospheric air may be used for controlling temperature of the heating gases without departing from the spirit of my invention.

What I claim and desire to secure by Letters Patent is:

Apparatus for heating hydrocarbon oil including a heating chamber having a horizontal series of wall ports, and a combustion chamber in communication with the lower portion of the heating chamber beneath said ports, connected banks of heating coils in the heating chamber located respectively above and below the series of wall ports, means for supplying fluid to be heated to the lower bank of coils for flow successively through the respective banks, and means for returning spent gases through said ports to the space in the heating chamber between the banks of coils.
